CAR COUPLING MEANS

Virginia Terry, Gary, W. Va.

Application February 9, 1945, Serial No. 577,055

2 Claims. (Cl. 213—190)

1

This invention relates to coupling means which is especially, but not necessarily, adapted for use in coupling mine cars or equivalent conveyances.

In carrying out the principles of the invention I have evolved and produced novel coupling means which, it is believed, is possessed of requisite factors of strength, durability and freedom from liability to derangement of parts.

Secondly, I provide a coupler assemblage in which the female coupling head or unit is provided with a simple and practicable cam-type latch, the latter being remote controlled by a rocker shaft and a connection between same and said latch, whereby to provide an assemblage of parts which lends itself adaptable for coaction therewith of a companion male coupling head having a simple free link which is virtually self-locating and quickly and reliably engageable with said latch.

The principal novelty resides, it is believed, in the specific construction of said female coupling head, the especially shaped latch pivotally mounted thereon, spring means for holding the latch in normal retaining position, and the operating connection between the spring-held latch and car structure for conveniently and effectively releasing the latch and consequently the link on the male coupling head.

Other features and advantages will become more readily apparent from the following description and the accompanying illustrative drawings.

In the drawings, wherein like numerals are employed to designate like parts throughout the views:

Figure 1 is a perspective view, partly of a fragmentary type, showing the aforementioned female coupling head and complementary appurtenances directly cooperable therewith.

Figure 2 is a top plan view of the male coupling head.

Figure 3 is a top view showing the head in section with the rest of the mechanism removed, this being the female coupling head.

Figure 4 is a view like Figure 3, showing the other head, that is, the male head, with the link removed.

Figure 5 is a central vertical sectional view through the female coupling head, with parts in elevation.

Figure 6 is a similar central vertical sectional view through the male coupling head.

Figure 7 is an elevational view, somewhat similar to Figure 5, but showing the parts mainly in elevation with the latch lifted to releasing position.

2

Figure 8 is a rear end elevational view of the female coupling head.

Figure 9 is a perspective view of the special latch.

Referring now to the drawings by distinguishing reference numerals, it will be seen that the female drawhead or coupling proper is denoted by the numeral 10. It is characterized by a sector-shaped shell having its flaring end formed into a suitable mouth defined by a beveled lip 11 and cam-surfaced, opposed side walls 12. This shell is bolted, or otherwise secured, as at 13, to a suitable base, for instance, a shelf-like extension 14 on the body 15 of the car or other conveyance or vehicle. The top wall thereof (see Fig. 5) is provided with a latch entrance and clearance slot 16 and at one end of the slot with upstanding lugs 17. The latch 18 is pivotally mounted therebetween, as at 19, (see Figs. 1 and 8) and as shown in Figure 9, one edge of the latch functions as a cam 20 and the free end is rounded, as at 21, and the beak is fashioned into a detent 22 receivable in a keeper seat 23 on the interior of the coupling head, as shown in Figure 5. As shown in Figures 1 and 8, the latch is provided with an externally arranged adapter bar 24 which extends beyond the diverging side walls of the coupling head, the extending ends being connected with coiled springs 25 anchored on retaining pins 26 on said head. The springs exert a normal downward pull and thus keep the latch seated in the retaining position illustrated in Figure 5. Attached to the central portion of the bar 24 is a clip 27 having a chain 28 connected with a rocker arm 29 on the central portion of the rocker shaft 30. The latter is mounted in appropriate bearing brackets 31 on the support 15. The rocker shaft is provided with lateral ends 32 which serve as handles. There is also a U-shaped fixture 33 bolted, or otherwise secured, to the support, and this underlies the arm 29 and constitutes a suitable stop and rest therefor. The latch rocks toward its pivot means and travels in and out through the slot 16 in the coupling head. It is normally closed, as shown in Figure 5, but is susceptible of being raised to releasing position, as shown in Figure 7. This is accomplished through the medium of the rocker shaft, handles, rocker arm and pull chain connection shown and described.

The numeral 15a designates a support corresponding to the support 15, while 14a is the support for the male coupler head 34. This is also of sector-shaped or dovetailed form and of appropriate shape to accommodate the so-called free link 35. The link is anchored by a bolt, pin,

or the like, 36. It protrudes through the open mouth and is in readiness to slip into the coupling head 10. When the coupling heads are brought together, the link unseats the latch by cam action, whereupon the latch is re-seated by the springs, thus effectively coupling the link to said head 10. The release of the link is effected by disengaging the latch, as brought out advantageously in Figure 7.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and arrangement of parts may be resorted to in actual practice so long as no departure is made from the invention as claimed.

I claim:

1. Coupling means comprising a hollow sector-shaped head having a slotted top wall, said top wall being provided with upstanding lugs, a latch pivoted between said lugs and depending and swingable in and out through the slot, the free swingable end of said latch being rounded, the lower edge thereof being inclined to provide a cam, said cam merging into the rounded end to define a detent, a cross-bar secured intermediate its ends to the exposed upper pivoted end

portion of said latch, said bar extending at its opposite ends beyond adjacent surfaces of said coupling head, coiled springs connected to the extending ends of said bar, and means anchoring the springs on said coupling head.

2. Coupling means comprising a hollow sector-shaped head having a slotted top wall, said top wall being provided with upstanding lugs, the latter on opposite sides of one end portion of said slot, a latch pivoted at its outer upper end between said lugs and having its opposite free end swingable in and out through said slot, the free swingable end of said latch being rounded, the lower edge thereof being inclined to provide a cam, said cam merging into the rounded end to define a detent, a cross-bar secured intermediate its ends to the exposed upper pivoted end portion of said latch, said bar extending at its opposite ends beyond adjacent surfaces of said coupling head, coiled springs connected to the extending ends of said bar, means anchoring the springs on said coupling head, supporting means for said head, a rocker shaft mounted for oscillation in bearings on said supporting means, a rocker arm on said shaft, a chain connection between the rocker arm and cross-bar, and a substantially U-shaped stop fixedly mounted on said support and underlying said rocker arm and constituting a stabilizing rest for said arm.

VIRGINIA TERRY.
